Fig. 1

Fig. 2

FIG. 1 is a perspective view of a transmission embodying my new design, with the shift lever broken away in all views to indicate indeterminate length;

FIG. 2 is a front elevational view thereof;

FIG. 3 is a top plan view thereof, it being understood that the rod has been shown fragmentarily at the top for convenience of illustration;

FIG. 4 is a right side elevational view thereof;

FIG. 5 is a left side elevational view thereof;

FIG. 6 is a bottom plan view thereof; and

FIG. 7 is a rear elevational view thereof.

I claim:

The ornamental design for a transmission, substantially as shown.
